(57) **CLAIM**

The ornamental design for a utility sink assembly with single basin, as shown and described.

DESCRIPTION

FIG. 1 is a top perspective view of a utility sink assembly with a single basin;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken lines in the drawings form no part of the claimed design.
